UNITED STATES PATENT OFFICE.

JUDSON R. TIBBLES, OF MACEDONIA, AND THAD S. KILGORE, OF SILVER CITY, IOWA.

GRAIN-BINDER ATTACHMENT.

1,200,902.

Specification of Letters Patent.

Patented Oct. 10, 1916.

Application filed August 28, 1915. Serial No. 47,856.

To all whom it may concern:

Be it known that we, JUDSON R. TIBBLES and THAD S. KILGORE, citizens of the United States, and residents of Macedonia and Silver City, in the counties of Pottawattamie and Mills, respectively, and State of Iowa, have invented a certain new and useful Grain-Binder Attachment, of which the following is a specification.

10 The object of our invention is to provide a binder attachment having a source of power for operating the working mechanism of any ordinary binder.

15 A further object is to provide such a binder attachment and a source of power suitably mounted thereon, with convenient mechanism for transmitting power from the source of power of the operative mechanism of the binder and to locate such transmitting mechanism as near as possible to the center of gravity of the binder and underneath the parts of the binder at the upper end of the elevator.

20 Still a further object is to provide in a binder having a reel and sickle, an attachment by which the reel is operated from the traction wheel of the binder, whereby the speed of the reel will be governed according to the speed of the binder's advance, which 25 binder is also provided with a suitable source of power for operating the other mechanism of the machine, whereby the heavy draft is taken from the animals which pull the binder.

30 35 A further object is to provide a device of the kind mentioned, in the form of an attachment which may be readily and easily installed on binders of ordinary construction, without substantially changing the 40 proper balance thereof, and also which may be so installed with almost no change in the arrangement of the parts of the binder.

45 Our invention consists in the construction, arrangement and combination of the various parts of the device, whereby the objects contemplated are attained as herein-after more fully set forth and pointed out in our claims, and illustrated in the accompanying drawings, in which:

50 Figure 1 shows a rear elevation of a binder partly in section, embodying our invention, taken on the line 1-1 of Fig. 2. Fig. 2 shows a vertical sectional fore-and-aft view of the binder taken just to the right 55 of the frame upon which the engine is

mounted, and Fig. 3 shows a top or plan view of the engine and the gearing mechanism connected therewith, the upper structure of the binder being removed for clearness.

60 One of the important advantages of our invention arises from the fact that certain parts of the mechanism may be mounted on an ordinary binder in the way of an attachment with almost no change in the arrangement of the binder parts. We have, therefore, not shown the binder parts in detail for in themselves alone, the parts of an ordinary binder are well known and form no part of our invention.

70 In the accompanying drawings, we have used the reference numeral 10 to indicate generally the frame of an ordinary binder having the axle 11, on which is fixed the large traction wheel 12, near one end of the 75 binder. At the other end of the binder is the small supporting wheel 13. The binder is provided with the ordinary sickle bar operating pitman 14. The binder also has the ordinary reel 15 on the shaft 16, operated 80 by suitable gearing devices from a short shaft 18, detachably mounted on the frame 10. Instead of connecting the sprocket 19 on the shaft 11 with the shaft 23 in the usual way, we connect it with the sprocket 20 on the shaft 18, by means of a chain 21. Above the shaft 18 is a shaft 18^a having a sprocket 18^b operated from a sprocket 18^c on the shaft 18 by a chain 18^d. The shaft 18^a is operatively connected with the reel shaft 16 by 90 suitable gearing devices 17. It will be understood that on binders of different makes, the shaft 18 may be connected with the reel in various suitable ways. It will thus be seen that one feature of our invention lies 95 in the arrangement of the parts, whereby the major part of the binder operating mechanism is run from a suitable source of power mounted on the binders, while the reel 15 is operated from the traction wheel 12. 100

105 It is well known that it is desirable to operate the reel from the traction wheel for the reason that it is desirable that the reel should feed or bend the upper parts of the straw and grain rearwardly over the sickle bar at a certain relative speed with relation to the forward travel of the machine. This advantage is retained in our device by operating the reel from the traction wheel. At the same time it is well known that the 110

strain upon draft animals is very serious, when all of the mechanism is operated from the traction wheel. It is, therefore, our purpose to use an engine 22 for operating the rest of the operating mechanism of the binder. In this connection it may be mentioned that the operating mechanism of the binder, including the sickle bar, endless carrier, elevating mechanism and tying mechanism are all operated from a countershaft 23, usually located somewhat rearwardly in the machine from the shaft 11.

It may be mentioned that all binders now in use are very carefully balanced so as to locate the load as nearly as possible over the line between the centers of the wheels 12 and 13. It is therefore our purpose to so mount the engine 22 and gearing mechanism for connecting the same to the shaft 23 in such a way as to locate them as near as possible adjacent to the center of gravity of the machine. In order to accomplish this purpose, we have mounted the engine 22 upon arms 24, secured to the frame 10 near the axle 11 and extending rearwardly and upwardly in substantially parallel position.

Mounted in suitable bearings on the arms 24 just below and forwardly of the engine 22 is a shaft 25. On the shaft 25 is a sprocket gear 26 in line with a sprocket gear 27 on the engine shaft 28. The sprocket 26 is run from the sprocket 27 by means of a chain 29. On the arms 24 forwardly of the shaft 25 is a transverse shaft 30, on which is a sprocket gear 31, in line with a sprocket gear 32 on the shaft 25. A chain 33 travels on the sprockets 32 and 31 for transmitting rotary motion from the shaft 25 to the shaft 30. On the shaft 30 is a sleeve 34 on which is a sprocket 35. Formed on the sleeve 34 is a clutch member 36.

Slidably but non-rotatably mounted in any suitable way on the shaft 30 is a sleeve 37 on which is a clutch member 38 adapted in one position to coactingly engage the clutch member 36 for transmitting rotation from the shaft 30 to the sleeve 34 and sprocket 35. The sleeve 37 is operatively connected with a lever 39 pivoted at one end to the frame of the machine, and at the other end to a link 40. The link 40 is operated by means of a lever 41. The sprocket gear 35 is in line with a sprocket gear 42 on the shaft 23 and transmits power thereto by means of a chain 44.

It is well known that ordinary binders have over the wheel 12 frame work for supporting the upper end of the elevating mechanism, knotting or tying mechanism and a suitable bundle receptacle.

It is our purpose to so arrange the arms 24 that the shaft 30 may be located beneath the upper portion of the machine, just described, and as near as possible to the shaft

11, varying as little as possible from the balance which is maintained by the ordinary binders.

The ordinary grain binder now in common use is so constructed and arranged that the weight is carefully balanced over the main axle. The operative mechanism is also arranged so that said mechanism may be operated from the large traction wheel 12 by means of power transmitted from said large traction wheel to the shaft 23. Our device is made as an attachment capable of being mounted on the ordinary binder now in use, of different makes, kinds and sizes with a minimum of interference with the ordinary operative mechanism, with a minimum disturbance on the balance of the binder, which attachment can be easily and quickly mounted on the ordinary binder frame.

The features of construction of our device, whereby we accomplish the things just mentioned lie in the construction and arrangement of the parts such as the arrangement of the engine on the bracket arms in such a way that its shaft is parallel with the shaft 23. It will readily be seen that such an arrangement of the engine enables us to locate the engine closer to the main axle 11 than is the case where the engine is located with its shaft arranged fore-and-aft in the machine.

We accomplish the purpose of a minimum disturbance of the balance of the binder by using a comparatively small sized high speed engine with a reduced speed gearing, including a suitable clutch all mounted on the bracket arms, so that the attachment can be operatively connected with the shaft 23 for operating said shaft at substantially the same speed at which it would be operated from the large drive wheel in binders of ordinary construction. By the use of the reduced speed gearing, we are able to use a high speed engine but low weight engine sufficient to operate the mechanism of the binder and yet so light that it does not interfere greatly with the balance of the machine. If a low speed engine were used, it would be necessary to use a high power engine, and therefore a comparatively heavy one to accomplish the purpose of running the binder mechanism under all the various surface conditions. By using the light, but high speed gearing, the power is applied at substantially the same point as it would ordinarily be applied from the traction wheel, so that there is no disturbance of the ordinary binder mechanism.

It will be understood that the sickle operating mechanism, the platform and endless carrier thereon, the operating mechanism, and cutting and binding mechanism may be the same as that used in ordinary binders now on the market.

We understand that some changes may be made in the construction and arrangement of the parts of our improved attachment without departing from its essential features and purposes, and it is our intention to cover by our present application any such changes which may be included within the scope of our claims.

It will be noted that our invention may be made by simply adding an attachment to the ordinary binder. The arms 24 having their peculiar shape for supporting the shafts 25 and 30 may be secured to the frame of any binder, by the means of supporting brackets 50, which may be varied somewhat in size and adjustment, the source of power and gearing mechanism herein shown may be mounted on any binder, and it is very easy to arrange the sprockets of the attachment and to place as many links in the various chains as is necessary to accomplish the purpose, and secure proper adjustment. The sprockets 19 and 20 are readily and easily mounted on the ordinary shafts with very slight modification of the other parts.

We claim as our invention.

1. The combination of a binder having a reel and having other mechanism adapted to coat with the reel in the cutting and binding of grain, a traction wheel, a shaft mounted on the frame of the binder, means for imparting rotation to said shaft from said traction wheel, a second shaft mounted on

the frame of the binder above said first shaft, sprocket gears on said shafts, a chain on said sprocket gears, and means for operatively connecting said second shaft with said reel, said means comprising a third shaft, operatively connected with the reel and coacting gearing devices on the second and third shafts.

2. In a device of the class described, the combination of a frame having a grain harvesting mechanism thereon with an attachment comprising a bracket, means for detachably mounting said bracket on said frame, an engine on said bracket, a pair of transverse parallel shafts mounted on said bracket, means for transmitting power from the engine to one of said shafts, means for transmitting power from the first to the second shaft, said means being so arranged as to rotate the second of said shafts more slowly than the engine shaft is rotated, means for transmitting power from the second of said shafts to the harvesting mechanism on said frame, and a clutch device for operatively connecting and disconnecting said last named means with said second shaft.
